UNITED STATES PATENT OFFICE.

WILLIAM E. NAGLE, OF PITTSBURGH, PENNSYLVANIA.

TOOL.

1,314,690.

Specification of Letters Patent.

Patented Sept. 2, 1919.

Application filed January 8, 1919. Serial No. 270,226.

To all whom it may concern:

Be it known that I, WILLIAM E. NAGLE, a citizen of the United States, and a resident of Pittsburgh, in the county of Allegheny 5 and State of Pennsylvania, have invented a new and useful Improvement in Tools; and I do hereby declare the following to be a full, clear, and exact description thereof.

My invention relates to tools, and has 10 special reference to what are known as milling tools, in which the cutters are formed from a high speed tungsten steel or other high grade metal, and the body for holding the cutters is formed from low carbon steel 15 or other low grade metal.

The object of my invention is to provide a cheap, simple and efficient milling tool, in which the teeth or cutters are capable of being easily and conveniently inserted in the 20 body and removable therefrom, will be prevented from shifting sidewise or tipping on the body when in use, and when applied to the body will be practically as strong and rigid as solid milling cutters which 25 are formed as integral parts of such body.

To these ends my invention consists, generally stated, in the novel arrangement, construction and combination of parts, as hereinafter more specifically set forth and de- 30 scribed and particularly pointed out in the claims.

To enable others skilled in the art to which my invention appertains to construct and use my improved tool, I will describe the 35 same more fully referring to the accompanying drawing, in which:

Figure 1 is a side elevation showing one- 40 half of the ordinary form of milling tool, which is partly broken away, and has my invention applied thereto;

Fig. 2 is an edge view of the same; and

Fig. 3 is a perspective view of one of the cutters removed.

Like symbols of reference herein indicate 45 like parts in each of the figures of the drawing.

As illustrated in the drawing A represents the milling tool as a whole which has its body 1 formed of low grade metal, such as 50 low carbon steel and is of the usual or well known construction, in which such body is of the ordinary circular disk shape of any desired diameter and of a thickness somewhat less than the width of the cut to be 55 made by the cutters hereinafter described. This body 1 is provided with the usual

radial slots 2, which extend into such body from the periphery 3 of the same, and are adapted to receive the removable cutters 4. The cutters 4 are formed of high grade 60 metal, such as high speed tungsten steel, and of such a length that when inserted into the slots 2, they will have their ends 4' extend beyond the side faces 1' of the body 1. The cutting edge 5 formed on one side 5' of the cutters 4 extend beyond the periphery 3 of the body 1 when such cutters are in place within the slots 2. A lug 6 is formed on the side 5' of the cutters 4 and it is formed preferably semi-circular in 70 shape for fitting within a like shaped seat 7 formed at one side of the slots 2 when the cutters are in place within said slots. A filister head screw 8 is screwed into a threaded hole 9 along side of the seat 7 by 75 its threaded shank 10 and its head 11 is adapted to extend over and engage by a portion of the same with the outer end of the lug 6 on the cutters 4 when such shank is screwed down to place. The other por- 80 tion of the head 11 on the screw 8 will thus be brought down into a counter sunk slot 11' in the periphery 3 of the body 1 when such screw is in place.

It will thus be seen that when the cutters 4 are inserted in place within the slots 2 in the body 1 and secured therein by the screw 8 engaging with the outer ends of the lugs 6 on the cutters, such cutters will be held rigid and tight in such body, and in case 90 one of such cutters needs sharpening, or has become broken and needs repairing, it can readily be removed for such purpose or re- 95 moved when desired by simply unscrewing the screws 8 and lifting out the cutters.

It will also be seen that such cutters will always remain securely in place until it is desired to remove the same, and secure against lateral movement, tilting and displacement and such cutters will not be required to be 100 made of special shapes for being held in place, as in the ordinary forms of these removable cutters, so that they will be practically no more expensive to manufacture than the ordinary cutters, while at the same 105 time a milling tool is provided in which the cutters can be worked and operated successfully under any conditions, either on side or face, and can perform the heaviest duty without the cutters being displaced.

It will be obvious that my improved construction can be applied to tools other than

milling tools and that the metals composing the same can be varied, while the shape of the lug on the cutter may be varied, and provision is made by the metal between the 5 lug and screw shank to allow for redrilling or enlarging the hole for such shank in case of wear.

Various other modifications and changes in the design and construction of my improved tool may be resorted to, without departing from the spirit of the invention as defined in the appended claims, or sacrificing any of its advantages.

What I claim as my invention and desire 15 to secure by Letters Patent is:

1. In a tool, the combination with a body having slots on its periphery, of removable cutters adapted to be inserted in said slots, a lug on one side of each of said cutters 20 adapted to engage with a seat in said slots to prevent lateral movement and displacement of the cutter in its slot, and means engaging said lug for holding the cutter in its slot.
- 25 2. In a tool, the combination with a body having slots on its periphery, of removable

cutters adapted to be inserted in said slots, a lug on one side of each of said cutters adapted to engage with a seat in said slots to prevent lateral movement and displacement of the cutter in its slot, and a screw 30 engaging with a threaded hole along side of each of said slots and with the lug for holding the cutter in its slot.

3. In a tool, the combination with a body 35 having slots on its periphery, of removable cutters adapted to be inserted in said slots, a lug on one side of each of said cutters adapted to engage with a seat in said slots to prevent lateral movement and displacement of the cutter in its slot, and a headed screw engaging with a threaded hole along side of said slots and by its head with the outer end of said lug for holding said cutter in its slot.

In testimony whereof, I, the said WILLIAM E. NAGLE, have hereunto set my hand.

WILLIAM E. NAGLE.
